CLAIM

The ornamental design for a body wrap as shown and described.

DESCRIPTION

FIG. 1 is a perspective view of a body wrap.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof.

FIG. 8 is a perspective view of the body wrap in use; and,

FIG. 9 is another perspective view of the body wrap in use.

The broken-line outline of the partial human figure illustrates how the claimed design may appear when worn and forms no part of the claimed design. The portion of the body wrap rendered in broken lines depicts environmental structure that forms no part of the claimed design.
